CLAIM

The ornamental design for an electronic device with light display, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top view of an electronic device with light display showing the claimed design;

FIG. 2 is a front view thereof;

FIG. 3 is a rear view thereof;

FIG. 4 is a left side view thereof, the right side being a mirror image thereof; and,

FIG. 5 is a bottom view thereof.

The broken lines in the figures show portions of an electronic device with light display that form no part of the claimed design.
